SHAKER DISPENSER OR SIMILAR ARTICLE

Angela D. Lisante, 85-60 116th St.,
Richmond Hill, N.Y.

Filed Feb. 1, 1965, Ser. No. 83,647

Term of patent 14 years

(Cl. D44—22)

FIG.1

FIG.2

FIG.4

FIG.5

FIG. 1 is a perspective view of a shaker dispenser or similar article showing my new design, wherein the dispensing closure is of a diameter substantially equal to that of the upper spherical portion of the dispenser;

FIG. 2 is a side elevational view thereof;

FIG. 3 is a side elevational view of a shaker dispenser showing another embodiment of my new design wherein the dispensing closure is of a diameter less than that of the upper spherical portion of the dispenser and substantially equal to that of the neck of the dispenser;

FIG. 4 is a top plan view thereof; and

FIG. 5 is a reduced scale bottom plan view thereof.

I claim:

The ornamental design for a shaker dispenser or similar
